LOUDSPEAKER

Gabriel E. Sundstrom, Chicago, Ill., assignor to
 Sundstrom Pressed Steel Co., Chicago, Ill., a
 corporation of Illinois

Application October 17, 1936, Serial No. 106,093

1 Claim. (Cl. 179—117)

This invention relates to loud speakers of the general type now more or less commonly used in connection with radio receiving apparatus and for other sound amplification purposes.

The main objects of the invention are to provide a loud speaker construction having a greater electrical and magnetic efficiency; to provide a structure of high efficiency but of simplified construction; to provide an improved construction for certain parts of such a loud speaker; and in general, it is the object of the invention to provide an improved loud speaker construction of the type referred to.

This application is continuation in part of my copending application Serial No. 61,883, filed February 1, 1936.

In the drawing:

Fig. 1 is a vertical cross section of a loud speaker embodying the present invention;

Fig. 2 is a front view of a portion of the structure shown in Fig. 1;

Figs. 3, 4, 5 and 6 illustrate successive steps in the production of the form of field member illustrated in Figs. 1 and 2;

Fig. 7 is a plan of a blank embodying another arrangement for joining its ends to form the field member; and

Fig. 8 is a perspective of the field member formed from the blank shown in Fig. 7.

Referring now to the drawing, the loud speaker construction illustrated in Fig. 1 embodies a main element or magnetic field member designated 10 which, in this instance, is formed of a flexible soft metal member bent to closed loop form as illustrated. The member 10 is illustrated separately in Fig. 6 from which it will be seen that it is formed from an elongated blank or strap of sheet metal bent to the form indicated.

Front and back walls 11 and 12, respectively, of the field member 10 are provided with openings 13 and 14, respectively. The top and bottom or opposite end walls 15 and 16 respectively, of the field member, are in this instance illustrated as being somewhat shorter than the front and back walls 11 and 12, the relative lengths of the walls being, of course, suited to the size of magnetic coil, such as 17, to be positioned within the field member, or to other requirements of the speaker to be made.

A pole piece 18 of suitable magnetic metal and usually of cylindrical shape, is assembled with the field member by first positioning the coil 17 within the field member and then inserting the pole piece through the opening 13 in the front wall of the field member, through the coil 17 and

then into the opening 14 in the rear wall of the field member. The openings 13 and 14 are preferably simultaneously machined to finished sizes by suitable means such as a reamer which may embody an end portion which will provide the opening 14 of a predetermined diameter, and another portion which will ream the opening 13 to predetermined size co-axially aligned with the opening 14. Reamers embodying the necessary two parts for simultaneously reaming the said opening are well known tools and therefore not illustrated.

As already indicated when the pole piece 18 is inserted, a magnetic coil 17 is also assembled in place. The coil 17 is normally wound on a suitable sleeve element through which the pole piece 18 may be passed. The fit of the pole piece 18 in the sleeve of the coil 17 is preferably a fairly snug but slideable fit. The pole piece is inserted, rear end first, through the voice coil opening 13 until the rear end reaches the opening 14. The opening 14 is made of such size that the rear end of the pole piece must be forceably driven into said opening, which, when done, results in a rigidly and practically permanently mounted and positioned pole piece. If required, a suitable ring or other gauge device may be employed for insuring accurate centering of the front end of the pole piece in the voice coil opening 13 which is of course large enough to receive a voice coil 19 carried by a cylindrical apex extension 20 of a cone or tympanum 21. The tympanum 21 may be mounted in and carried by a so-called basket 22, preferably of stamped sheet metal construction, the same being attached to the field member 10 by any suitable means, for example, through the agency of ears and welding as explained in my said copending application.

A transformer 23, from which varying electrical currents pass to the voice coil 19, may be attached to the speaker through the agency of a suitable bracket 24 secured to the field member 10 by welding or otherwise.

The sheet metal blank from which the field member 10 is made (illustrated in Fig. 3), embodies the back wall portion 12 provided with the punched in opening 14, end wall portions 15, 16, and end sections 11a and 11b respectively, which together constitute the front wall 11 of the field member. As indicated, the end portion 11a is provided with a semi-circular recess 13a disposed centrally of the end of the blank, and a pair of dovetail shaped recesses 25, 25. The opposite end of the blank is also provided with

5 a semi-circular recess 13b disposed centrally of the width of the blank and a pair of dovetail shaped tongues 26, 26 respectively, disposed on opposite sides of the recess 13b. The recesses 13a and 25, 25 are respectively complementary to the recess 13b and tongues 26, 26.

10 The second step in forming a field member from the blank illustrated in Fig. 3 is to bend down the end portion 11a to substantially right angles to the main body portion of the blank and the end portion 11b to an angle somewhat less than 90 degrees, substantially as illustrated in Fig. 4. A third step is illustrated in Fig. 5, where the end portions 15 and 16 are bent to 15 right angular relation to the central or back portion 12. A final step consists in further bending the end portion 11b of the blank into co-planar relation with the end portion 11a, in which position the dovetail shaped tongues 26, 26 will enter 20 and lock with the dovetail shaped recesses 25, 25. The dovetail tongues and slots are made of such relative proportions that when they are interengaged, as shown in Figs. 2 and 6, the meeting ends are more or less jammed into one 25 another so that there is tight, intimate engagement between the ends of the wall portions 11a and 11b. By reason of the tight fitting interlocked connection resulting from the described arrangement, other securing or connection between the blank ends, for example, welding, is 30 not required.

35 The hole 14 may be employed for guiding purposes during any of the forming operations where such use is feasible, and it will of course be evident that the procedure may be inverted, i. e., the blank ends bent upwardly instead of downwardly, to meet practical considerations in press maintenance and operation.

40 Suitable punch-press squaring operations may be employed for insuring the desired squareness of the field member.

45 Because of the increased area of contact between the meeting ends of the blanks, incident to the described end connections, certain desirable electrical effects are obtained. It also will be apparent that by effectively interlocking the meeting ends of the blanks as described, the practicability of forming the field member from a blank with prepunched pole piece and voice 50 coil openings in the front and back of the field member is enhanced. The previously described reaming operation is capable of finishing the openings so as to obtain the required, accurate, coaxial alignment of the holes.

55 The arrangement shown in Figs. 3 to 6 inclusive, has certain electrical or magnetic advan-

tages, at least theoretically. However, a very efficient and satisfactory construction, which, for practical purposes is preferable, is shown in Figs. 7 and 8. In the arrangement therein shown, the blank is provided with two punched openings 5 13 and 14 in portions of the blank which will ultimately form the front and rear walls of the field member. As indicated in Fig. 7, the blank comprises a top wall portion 15, front and rear wall portions 11 and 12 respectively, and end 10 portions 16a and 16b which cooperatively form the bottom wall 16 of the field member.

15 The end portions 16a and 16b are respectively provided with a dovetail shaped recess 27 and a complementary tongue 28, the said recess and 20 tongue being aligned, preferably centrally of the width of the blank. By bending operations similar to those illustrated in Figs. 3 to 6 inclusive, the blank shown in Fig. 7 may be bent to form the closed-loop field member illustrated in Fig. 8 25 wherein the dovetail joint between the ends of the blank are located in the bottom wall 16 of the field member. Squaring and reaming operations as previously mentioned may be performed on the field member shown in Fig. 8 and a suitable pole piece may be mounted by press fitting or otherwise as may be preferred.

30 The described magnetic field structures are especially advantageous first, in that the required manufacturing operations are very simple and inexpensive to perform, and secondly, in that they provide an efficient magnetic flux circuit, thereby adding to the efficiency of the loud speaker. The efficiency of the magnetic flux circuit is due in considerable measure to the adequate connection between the meeting ends of the blank when formed into the closed loop illustrated.

35 Changes in the construction may be made without departing from the spirit of the invention, the scope of which should be determined 40 by reference to the following claim, the same being construed as broadly as possible consistent with the state of the art.

I claim:

45 A magnetic field member for a loud speaker, comprising an elongated flexible soft metal strap bent to form a closed loop, a portion of said loop being provided with a voice coil opening, said strap having meeting end portions provided with means of dovetail form tightly interfitted in 5 jammed relation throughout the width of said strap and serving to lock said end portions against endwise separation whereby to maintain said loop in closed form and provide an efficient magnetic flux circuit.
